UNITED STATES PATENT OFFICE

2,445,214

VERTICAL SHRINKER APPARATUS

John Lee Ferguson, Joliet, Ill., assignor to J. L. Ferguson Company, Joliet, Ill., a corporation of Illinois

Application January 28, 1946, Serial No. 643,897

15 Claims. (Cl. 93—55.1)

1

This invention relates to a package processing machine, more particularly to an apparatus wherein package caps are fitted tightly upon package bodies by forming means which operate upon packages after the caps have been initially loosely placed upon the bodies.

More particularly, the invention relates to machines wherein the caps are shrunk onto, or made to conform, to the package bodies by enveloping the capped portion of the package by heat imparting means. Attention is directed to J. L. Ferguson Patent No. 1,540,321 for a comprehensive description of the cap shrinking process and the advantages gained therefrom. The novel features embodied in and the advantages of the present machine may be best appreciated as they are pointed out progressively as the structure of the apparatus is hereinafter described. Such description will be given in connection with the accompanying drawings, in which

Fig. 1 is an elevational view partially in section of an apparatus embodying the present invention;

Fig. 2 is a plan view of the machine shown in Fig. 1;

Fig. 3 is an end elevational view taken from the right-hand side of the apparatus of Fig. 1;

Fig. 4 is a fragmentary elevational sectional view of a portion of the apparatus; and

Fig. 5 is a greatly enlarged view of one portion of the sectionalized showing of Fig. 4, the parts shown in said enlarged view being made somewhat out of proportion in order to emphasize certain features of the invention.

The machine comprises a lower base 10 having lower legs 11—11 supporting the same. Upper legs 12 project upwardly from the corners of the base member 10 and support on their upper ends an upper base 13. A stationary hollow center post 14 is seated in a bottom mounting 15 and extends upwardly through the upper base 13 constituting a support for a cylindrical sleeve 16 which latter has a flared bearing portion member 17 at its lower end. This sleeve 16 is vertically adjustable along the center post 14 for purposes to be hereinafter described. The adjustment is accomplished by turning cap 18 which is secured by screw 19 to interiorly threaded sleeve or adjusting nut 20 in association with an adjusting nut collar 21. An inwardly projecting collar 20a is included in sleeve 20, and in combination with the cap 18 so embraces a collar 21 fixed to the post 14 that rotation of said cap 18 and sleeve 20 moves sleeve 16 vertically. What may be termed the shrinker assembly

2

comprises a plurality of shrinker units 22 which consist of shrinker head bearings 23 in which shrinker head sleeves 24 are adapted to move vertically, openings 25 on the inner sides of said bearings 23 permitting the movement vertically thereof of shrinker head guide studs 26 attached to said shrinker head sleeves 24. Head cam rolls 27 are rotatably mounted on said studs 26, said cam rolls 27 riding in a camway 28 formed at the periphery of a sleeve and dish member 29 surrounding and secured to the vertically movable sleeve 16. The shrinker head units are supported on a shrinker head support 30, which latter carries a depending cylindrical supporting and connecting collar 31.

The entire rotary shrinker head assembly is rotatable about the central supporting post 14, being movable thereabout on a ring bearing 11a positioned between the outwardly extending portion 17 and a depending lip 30a on the shrinker head support 30.

Rotatably movable member 32 also surrounds the central post 14 and has a flat turntable 33 secured thereto, this member 32 and 33 being also adapted to rotate about the post 14 on bearing 34, being connected to the upper portion of the assembly by the supporting member 31. The turntable 33 provides a support for cans as the latter are carried through the shrinking cycle. Can carriers 35 are secured to the member 32 and rotate therewith to maintain the cans in vertical alignment with shrinker heads 36. Said heads 36 are secured to the bottoms of the shrinker head sleeves 24 by friction fit or other similar securing means whereby they may be removed or detached from the sleeves when a change of heads is made. Said heads move vertically with said sleeves as the latter reciprocate vertically in shrinker head bearings 23.

Inside of each shrinker head 36 is positioned an ejector disk 37 mounted on ejector rod 38 the indicated threaded mounting of the disc on the rod 38 permitting ready substitution of differently sized disks as required by the can cap diameter. An ejector rod collar 39 is fixed to each ejector rod 38 and forms a lower limit member for an ejector spring 40. Also secured to each ejector rod 38 are collars 41 and 42 which define the limits of movement of said rod vertically by contacting an ejector rod stop 43 mounted on the upper ends of ejector rod stop spacers 44. Head sleeve caps 45 are positioned as shown to confine the upper ends of ejector springs 40.

Thus it will be seen that as the shrinker heads 36 move downwardly, the can caps press up-

wardly against the ejector disks and cause the ejector springs 40 to be compressed to maintain said caps under yielding pressure as they are being shrunk tightly onto the can bodies. Moreover, when the shrinker heads are lifted, the ejector disks are positively thrust relatively downwardly by the springs 40 to assist the positive release of the capped cans from the shrinking heads.

Another important feature of the ejector disk mechanism resides (1) in the proportioning of the disk with respect to the cans upon which the caps are shrunk and/or (2) in the structure included in the disk itself. Before describing the just referred-to structure, the reaction of the can structure to the shrinking of the cap thereupon should be understood. Can bodies are frequently formed by subdividing spirally wound tube sections. It has been found that shrunken capped packages sometimes exhibit a regrettable lack of tightness despite there seeming to be nothing wrong with the shrinking mechanism and despite the fact that the cap has been shrunk the prescribed degree by such shrinking heads. The present invention is in part based on a careful study of the possible reasons for such inadequate shrinking and the devisement of means operative during the shrinking for insuring against the previously experienced inadequacies. Looking for instance at Fig. 4, the present inventor has discovered what seems to be the reason for these inadequacies. In short, as the cap is shrunk onto the can body, a definite positive pressure is exerted by the lip of the cap horizontally inwardly against the upper edge of the can body. Accordingly as the weaker upper edge of the can body buckles inwardly, the shrunken cap cannot press tightly thereagainst to provide the seal which has been one of the outstanding advantages of shrunken caps as closures for can bodies. It has been discovered that by adjusting the dimensions of the disk 37 with respect to the inner diameter of the can body, i. e. by making the disk diameter slightly less than the diameter of the inside of the can body, and/or by providing said disk 37 with a quarter circle lower edge 37a, very desirable results are obtained.

The reasons why such dimensioning and/or supplying of the radius at 37a prevents the above shortcomings of shrinking caps on can bodies may be best understood from an examination of the greatly enlarged view of Fig. 5. As the disk 37 is pressed downwardly even very lightly against the can cap, the material of the latter is forced very slightly downwardly to lock against the inside edge of the upper portion of the can. Thereafter as the lip of the cap shrinks inwardly and tends to conform tightly with the outer upper edge of the can body, the latter cannot collapse or buckle, wherefrom an exceptionally tight seal ensues as the cap is shrunk onto the can body. The dimensions of Fig. 5 may be somewhat out of proportion, but have been so shown in order to emphasize the manner in which the heretofore described dimensioning of the disk 37 and/or the rounding of the lower edge 37a thereof function to prevent the collapse of the upper edge of the can body. The term "and/or" is used deliberately because while the rounded edge 37a is of value, there may be materials and can dimensions which are such as to eliminate the necessity for this rounded edge.

The cans C (see Fig. 2) are presented to the shrinking heads via a belt conveyor 50 which travels from left to right (as indicated by the

arrows) over idlers 51, 52, 53 and 54, the belt being driven by a pulley 55 which is in turn chain-driven through chain 56 passing around small sprocket 57 mounted on the same shaft as large sprocket 58. A chain 59 extends between the sprocket 58 and sprocket 60 mounted on shaft 61 projecting from a speed reduction mechanism 62. Guide rails 63 are mounted to confine the cans as they are fed from left to right by the conveyor belt 50.

A shaft 64 projects vertically from speed reduction mechanism 62, the power being supplied thereto via a motor 65, a belt or chain 66 and a pulley 67. A small driving sprocket 68 is fixed to said shaft 64 and a chain 68a engages said sprocket 68 to drive a plurality of other mechanisms, one of these being the sprocket 69 which is fixed to the sleeve on which the main shrinker head assembly is mounted. Other sprockets driven by said chain 68a will be referred to as the associated driven mechanisms are progressively described.

Star wheel 70 comprises an upper spider 72 and a lower spider 73, both mounted on star wheel shaft 74. The star wheel spiders 72 and 73 form a plurality of arcuate pockets 75 in the periphery of the wheel (six of such pockets being shown in the present illustration), said pockets flaring outwardly to form a plurality of can-arresting points 75a. A sleeve 76 surrounds the star wheel shaft 74 and a collar 77 is utilized to mount a bracket 78 carrying a set screw 79. A rotary pressure disk 80 is mounted on a shaft 81 secured to the bracket 78 by the set screw 79.

The pressure disk 80 is positioned so that the periphery thereof contacts the caps on the cans to produce sufficient pressure to insure positive travel of the cans with the conveyor belt, this being a desirable, if not a necessary provision, when handling empty cans. The star wheel 70 is provided with a six-toothed circular ratchet 82 having teeth 83 thereon, said teeth adapted to be engaged by the hook end 84 of a rod 85 pivotally mounted at 86. The other end of said rod 85 is provided with a roller 87 for purposes later to be described.

A feeding-in wheel 88 includes a plurality of can contacting arms 89 and is mounted on a shaft 90 which latter is driven by a sprocket 88a. The heretofore referred-to chain 68a passes around the sprocket 88a and moves the same in synchronism with the remainder of the apparatus elsewhere herein described. Thus the in-feeding member 88 is driven in synchronism with the shrinker head assembly so that a can is fed into position directly under a shrinking unit and is thereafter carried by a can carrier 35 in said position. The in-feeding wheel 88 and/or shaft 90 carries a cam 91 which, as the member 88 is rotated, moves the roller end 87 of the pivoted member 85 to release the hook end 84 of said member from engagement with one of the teeth 83 thereby to permit the star wheel 70 and that can which has been withheld from movement by being partially nested in one of the arcuate pockets 75 to be moved by the conveyor 50 so that the can may be picked up by an arm 89.

Thus as long as the hooked end 84 stands in the way of one of the teeth 83, the can arrested in the position of the can C in Fig. 2 cannot (even though it is urged rightwardly by the conveyor belt 50 against the contacted point 75a) turn said star wheel and pass further to the right. However, as each ratchet tooth 83 is released by the hook end 84, the arrested can is

enabled freely to move the star wheel and pass into position to be engaged by one of arms 89. However, as soon as one can has passed the star wheel, the roller 87 has been so cammed as to move the pivoted member 85 and cause the hooked end 84 to engage the next tooth 83. The star wheel 70 is thus so held that another can is then withheld (by being arrested by one of the points 15a and thereby partially nested in one of the arcuate pockets 15) from being fed 10 into engageable position by the member 88.

After a can has been positioned to be engaged by one of the arms 89, the latter, in conjunction with a can feeding-in guide 92, positively feeds the can around into position to be contacted by a can carrier 35 and thence to be placed under a shrinker head while the latter is in its most elevated position. Continued rotary movement of the shrinker head assembly about the central post 14 causes the shrinker head 36 now positioned just above the can under consideration to move downwardly as the roller 27 travels along the cam track 28. When the cap on the can is properly enveloped by the shrinking head 36, the shrinking cycle begins. Heat is imparted to the cap end of the can and as explained in the above identified Ferguson patent, the shrinkability of the material is taken advantage of to tighten the can cap on the can body. The shrinking cap is heated electrically by well known means which it is not thought are necessary here to explain.

After the shrinking cycle has been completed and the can under consideration has been moved circularly to the exit zone of the machine, the cam track 28 functions to raise the roller 27 and concurrently to raise the shrinker head from enveloping position with the can cap. Thereupon can discharge arms 100 on a can feeding-out member 101 are in position to go into operation positively to carry the shrunken capped can from the shrinking zone back onto the conveyor belt 50.

The hereinbefore referred to chain 68a, initially driven by engagement with sprocket 68, passes around and engages sprocket 101a which is fixed to a shaft 101b on which the member 101 is mounted. Said sprocket 101a is so toothed and dimensioned that the movement of the member 101 is properly timed and synchronized with the movement of the remainder of the apparatus.

When the cap shrinking process is completed, the ejector disk positively functions under the impulse of the ejector spring 40 to eject a can which for some reason or another may tend to stick in the ejector member as the latter is raised into non-operating position.

Thus a shrinking unit of patentably distinguishing degree of certainty of operation has been produced. This certainty of operation is insured because of the hereinbefore described mechanisms.

It is not intended that the description heretofore given of the invention and/or the showing thereof set forth in the drawings is limiting in any respect of the monopoly claimed by applicant. It is on the contrary intended that all claims hereinafter allowed, whether made initially or to be added (assuming that they are properly supportable by the drawings and/or specification and/or claims originally made herein), shall be the measure of the scope of the invention herein set forth. Accordingly, and with the foregoing in mind, what is claimed as new and is desired to be secured by Letters Patent is (remembering that claims broader than those

now included may hereafter be found properly includable herein):

1. In an apparatus of the character described, an assembly of shrinker heads, means for presenting cans having unshrunken caps thereon, means for in-feeding said cans progressively under an unoccupied head, means for operatively shrinkingly associating said heads with said capped cans as the latter are juxtaposed therewith and for maintaining said association through a predetermined shrinking cycle, and out-feeding means for positively disassociating cans from said shrinking means.

2. In an apparatus of the character described, an assembly of shrinker heads, means for presenting cans having unshrunken caps thereon, means for in-feeding said cans progressively under an unoccupied head, means for withholding said cans until said feeding means is in synchronism with an unoccupied head on said assembly, means for operatively shrinkingly associating said heads with said capped cans as the latter are juxtaposed therewith and for maintaining said association through a predetermined shrinking cycle, and out-feeding means for positively disassociating said can from said shrinking means.

3. In an apparatus of the character described, an assembly of shrinker heads, means for presenting cans having unshrunken caps thereon, means for in-feeding said cans progressively under an unoccupied head, means for withholding said cans until said in-feeding means is in synchronism with an unoccupied head on said assembly comprising a member provided with one or more pockets for positively holding the about-to-be presented can stationary and connecting means between said member and said in-feeding means for releasing said member to permit a can to be engaged by said in-feeding means in synchronism with the movement of said shrinker head assembly, means for operatively shrinkingly associating said heads with said capped cans as the latter are juxtaposed therewith and for maintaining said association through a predetermined shrinking cycle, and out-feeding means for positively disassociating said can from said shrinking means.

4. In an apparatus of the character described, an assembly of shrinker heads, means for presenting cans having unshrunken caps thereon, including a rotary member exerting pressure against said caps to insure positive travel of said cans as they are presented, means for in-feeding said cans progressively under an unoccupied head, means for operatively shrinkingly associating said heads with said capped cans as the latter are juxtaposed therewith and for maintaining said association through a predetermined shrinking cycle, and out-feeding means for positively disassociating cans from said shrinking means.

5. In an apparatus of the character described, an assembly of shrinker heads, means for presenting cans having unshrunken caps thereon, means for in-feeding said cans progressively under an unoccupied head, and means for operatively shrinkingly associating said heads with said capped cans as the latter are juxtaposed therewith and for maintaining said association through a predetermined shrinking cycle comprising a plurality of vertically oscillatable shrinker heads adapted to be positioned over the can caps and a camway for vertically moving a head into shrinking relation with each can as cans

are in-fed progressively and for maintaining said heads in said relation as the cans are moved from the in-feeding zone to an out-feeding zone, each of said heads being provided with a spring-biased ejector disk to maintain said caps under yielding pressure during the shrinking cycle.

6. In an apparatus of the character described, an assembly of shrinker heads, means for presenting cans having unshrunk caps thereon, means for in-feeding said cans progressively under an unoccupied head, and means for operatively shrinkingly associating said heads with said capped cans as the latter are juxtaposed therewith and for maintaining said association through a predetermined shrinking cycle comprising a plurality of vertically oscillatable shrinker heads adapted to be positioned over the can caps and a camway for vertically moving a head into shrinking relation with each can as cans are in-fed progressively and for maintaining said heads in said relation as the cans are moved from the in-feeding zone to an out-feeding zone, each of said heads being provided with a spring-biased ejector disk to maintain said caps under yielding pressure during the shrinking cycle, said heads and said ejector disks comprising demountable units to provide for substitution to accommodate cans of varying diameter.

7. In an apparatus of the character described, an assembly of shrinker heads, means for presenting cans having unshrunk caps thereon, means for in-feeding said cans progressively under an unoccupied head, means for operatively shrinkingly associating said heads with said capped cans as the latter are juxtaposed therewith and for maintaining said association through a predetermined shrinking cycle comprising a plurality of vertically oscillatable shrinker heads adapted to be positioned over the can caps and a camway for vertically moving a head into shrinking relation with each can as cans are in-fed progressively and for maintaining said heads in said relation as the cans are moved from the in-feeding zone to an out-feeding zone, and means for vertically adjusting the shrinker head and camway assembly to accommodate cans of varying height.

8. In an apparatus of the character described, an assembly of shrinker heads, means for presenting cans having unshrunk caps thereon, means for in-feeding said cans progressively under an unoccupied head, means for operatively shrinkingly associating said heads with said capped cans as the latter are juxtaposed therewith and for maintaining said association through a predetermined shrinking cycle comprising a plurality of vertically oscillatable shrinker heads adapted to be positioned over the can caps and a camway for vertically moving a head into shrinking relation with each can as cans are in-fed progressively and for maintaining said heads in said relation as the cans are moved from the in-feeding zone to an out-feeding zone, and means for maintaining a yielding pressure on said caps during the shrinking cycle.

9. In an apparatus of the character described, an assembly of shrinker heads, means for presenting cans having unshrunk caps thereon, means for in-feeding said cans progressively under an unoccupied head, means for withholding said cans until said in-feeding means is in synchronism with an unoccupied head on said assembly comprising a star wheel including a plurality of arcuate pockets adapted partially to embrace and hold stationary one of the being presented cans,

and connecting means between said wheel and said in-feeding means comprising a pivoted arm movable when said in-feeding means is properly positioned to permit rotary movement of said star

5 wheel and entry of the just held can into said in-feeding wheel in synchronism with the movement of said shrinker head assembly, means for operatively shrinkingly associating said heads with said capped cans as the latter are juxtaposed therewith and for maintaining said association through a predetermined shrinking cycle, and out-feeding means for positively disassociating said can from said shrinking means.

10. In an apparatus of the character described, an assembly of shrinker heads, a linear conveyor for presenting cans having unshrunk caps thereon, means for in-feeding said cans progressively under an unoccupied head comprising a rotary member having arms arranged to engage can

20 sides, a guide member, said arms and said guide functioning to feed said cans, and a can carrier to receive said thus-fed cans and maintain them in shrinker head receiving position, means for withholding said cans until said in-feeding means is in synchronism with an unoccupied head on said assembly comprising a member provided with one or more pockets for positively holding the about-to-be presented can stationary, and connecting means between said member and said in-

30 feeding means for releasing said member to permit a can to be engaged by said in-feeding means in synchronism with the movement of said shrinker head assembly, means for operatively shrinkingly associating said heads with said capped cans as the latter are juxtaposed therewith and for maintaining said association through a predetermined shrinking cycle, and out-feeding means for positively disassociating said can from said shrinking means.

40 11. In an apparatus of the character described, an assembly of shrinker heads, a linear conveyor for presenting cans having unshrunk caps thereon, means for in-feeding said cans progressively under an unoccupied head comprising a rotary member having arms arranged to engage can

45 sides, a guide member, said arms and said guide functioning to feed said cans, and a can carrier to receive said thus fed cans and maintain them in shrinker head receiving position, means for withholding said cans until said in-feeding means is in synchronism with an unoccupied head on said assembly comprising a member provided with one or more pockets for positively holding the about-to-be presented can stationary, and connecting means between said member and said in-

55 feeding means for releasing said member to permit a can to be engaged by said in-feeding means in synchronism with the movement of said shrinker head assembly, means for operatively shrinkingly associating said heads with said capped cans as the latter are juxtaposed therewith and for maintaining said association through a predetermined shrinking cycle, and out-feeding means for positively disassociating said can from

60 said shrinking means, said conveyor being positioned adjacent one side of said in-feed, said shrinker head assembly, and said out-feeding means wherefrom said cans are fed off said conveyor, the caps shrunk thereupon and thereafter returned to said conveyor while the latter continues its linear travel.

70 12. In an apparatus of the character described, an assembly of shrinker heads, means for positioning the shrinker heads over capped cans to shrink the material of said caps against the outer

portions of the cans to form a tight seal and means to hold the can body portion against which the caps are shrunk from moving and nullifying the expected seal between the shrunken cap and the can body.

13. In an apparatus of the character described, an assembly of shrinker heads, means for positioning the shrinker heads over capped cans to shrink the material of said caps against the outer portions of the cans to form a tight seal and means for forcing the planar portion of the can cap downwardly against the inside lip of said body to hold the can body portion against which the caps are shrunk from moving and nullifying the expected seal between the shrunken cap and the can body.

14. In an apparatus of the character described, an assembly of shrinker heads, means for positioning the shrinker heads over capped cans to shrink the material of said caps against the outer portions of the cans to form a tight seal and means to hold the can body portion against which the caps are shrunk from moving and nullifying the expected seal between the shrunken cap and the can body, said last named means comprising a member pressing downwardly against the cap at the point where said holding is desired to force a portion of said cap against the inside lip of said body.

15. In an apparatus of the character described, an assembly of shrinker heads, means for positioning the shrinker heads over capped cans to shrink the material of said caps against the outer portions of the cans to form a tight seal and means to hold the can body portion against which the caps are shrunk from moving and nullifying the expected seal between the shrunken cap and the can body, said last named means comprising a spring pressed disk of less cross-sectional dimension than the interior of the can body which disk presses a portion of said cap against the inside lip of said body.
